(57) **CLAIM**

The ornamental design for a scaffolding system, as shown and described.

DESCRIPTION

FIG. 1 is a bottom perspective view of the scaffolding system in accordance with the present design; FIG. 2 is a top perspective view thereof;

FIG. 3 is a front view thereof;

FIG. 4 is a rear view thereof;

FIG. 5 is a left side view thereof;

FIG. 6 is a right side view thereof; and,

FIG. 7 is a bottom view thereof.

The broken lines shown in the drawings illustrate portions of the scaffolding system that form no part of the claimed design.
